United States Patent Office

Des. 211,637

Patented July 9, 1968

211,637

FISH SPEAR

John C. McKusick, 3495 E. Pico Blvd.,
Los Angeles, Calif. 90023

Filed July 19, 1967, Ser. No. 7,881

Term of patent 14 years

(Cl. D22—22)

Fig. 1.

Fig. 2.

Fig. 3.

Fig. 4.

FIG. 1 is a perspective view of a fish spear with a portion of the handle shown in dash lines to indicate indeterminate length, showing my new design;

FIG. 2 is a side view of my fish spear;

FIG. 3 is a top view of my fish spear;

FIG. 4 is a bottom view of my fish spear.

I claim:

The ornamental design for a fish spear, substantially as shown.
